UNITED STATES PATENT OFFICE.

DAVID H. ALLEN, OF MIAMISBURG, OHIO.

TRAY FOR GLASSES.

No. 817,148.

Specification of Letters Patent.

Patented April 10, 1906.

Application filed July 28, 1905. Serial No. 271,694.

To all whom it may concern:

Be it known that I, DAVID H. ALLEN, a citizen of the United States, residing at Mi-
5 amisburg, in the county of Montgomery and
State of Ohio, have invented certain new and
useful Improvements in Trays for Glasses, of
which the following is a specification.

My invention relates to a tray for holding
glasses and the like, and principally adapted
10 for glasses of the variety which are provided
with a stem and base.

The object of my invention is to provide
a simple self-contained glass-holding tray
which will detachably receive and secure a
15 series of glasses.

Another object of the invention is that the
glass-holding members shall be simple and
light and project as little as possible from the
face of the tray, so that they will not add ma-
20 terially to the weight nor render the device
cumbersome and unsightly.

The features of my invention are more
fully set forth in the description of the ac-
companying drawings, forming a part of this
25 specification, in which—

Figure 1 is a top plan view of my tray and
glass-holders, showing one, or rather the base,
portion of a glass in position. Fig. 2 is a section
30 on line *x* *x*, Fig. 1. Fig. 3 is a section on
line *w* *w*, Fig. 1. Fig. 4 is a perspective view
of one of the holders. Fig. 5 is a perspective
view of one of the holder-brackets for mount-
ing the holders upon the tray.

A represents the tray, having the handle
35 portions *B* *B'* formed on the ends thereof.

a *a'* represent a bead formed around the
edge of the tray, the function of which will be
hereinafter described.

In the preferred form of construction the
40 glass-holders are made of wire tempered suffi-
ciently to enable the same when secured in
position to have a downward resilient action
for securely holding the glasses in position.
These holders are formed as follows: *1* *2* rep-
45 resent the ends of the wire adapted to be em-
bedded into the tray for securing the same to
the holder. The wire is bent at right angles
to the ends *1* *2*, forming the crossing axle-like
extensions *3* *4*, which are loosely mounted in
50 the slots *5* and *6*, formed in the upwardly-
extended limbs of the holder-bracket *7*, thereby
enabling the holder proper to yield up-
wardly. The wire is then extended forward,
forming the limbs *8* *9*, and then looped in-
55 ward, forming the yoke *10*, within which yoke
the stem of the glass is passed. In mounting

the holder upon the tray and to provide the
proper resiliency thereto it will be seen from
the drawings that the axle-like extensions *3* *4*
cross each other, thereby enabling the limb 60
portions *8* *9* to lie above the ends *1* *2*, bring-
ing the same into parallel alinement, thus en-
abling both limbs to bear with equal tension
upon the base of the glass. The yoke proper,
10, of the holder is bent slightly downward, 65
thereby providing greater tension upon the
base of the glass at the stem. The parts, as
combined, form a very strong holding me-
dium. The limb extensions *8* *9* are extended
a slight distance beyond the beaded edges *a* 70
a' of the tray. This enables the glass to be
easily inserted in position by engaging the
limb ends *8* *9* on the base of the glass, lifting
the glass slightly upward over the bead and
pushing the same in position upon the tray 75
without requiring the holders to be manipu-
lated by hand. The beaded edges of the
tray likewise form a lateral guard against
the base of the glass, preventing the same
from sliding out when the tray is held in a 80
vertical position, and thus cannot be removed
unless the base of the glass is raised over the
same.

It will be observed that the holders upon
each side of the tray are each composed of a 85
resilient wire, the opposite ends of which are
secured to the opposite ends of the tray, and
the intermediate portion of which is bent
upwardly and outwardly to form the stem-
receiving yokes, as previously described. As 90
the beaded edge lies above the tray the outer
receiving ends of the yokes press against this
beaded edge, and the inner or looped ends of
the yoke are bent downward preferably to
press against the base of the tray. This form 95
of holder is preferred, although it is not to be
regarded as a limitation, except where spe-
cifically claimed.

Having described my invention, I claim—

1. In a tray, a base provided with a beaded 100
edge, spring glass-holders secured to the tray
and provided with stem-receiving yokes ex-
tended outwardly over the said beaded edge,
substantially as described.

2. A tray, having a wire resiliently secured 105
thereto and bent to form a series of stem-re-
ceiving yokes, having U-limbs which engage
over the bases of the glasses and clamp them
against the tray, substantially as described.

3. In a tray, a base, provided with a bead- 110
ed edge, resilient glass-holders secured to the
tray and bent upwardly and outwardly to

form stem - receiving yokes overlying the beaded edge of the tray, and adapted to clamp the glasses against the base of the tray, substantially as described.

5 4. In a tray, a base provided with a beaded edge, resilient glass-holders secured to the tray and bent upwardly and outwardly to form stem-receiving yokes, the outer receiving ends of the yokes having a yielding engagement with the beaded edge and the inner loop ends of the yokes being bent downwardly to yieldingly engage the base of the tray, substantially as described.

10 5. A tray, having a series of stem-receiving yokes spring-hinged at their inner ends to the tray, the limbs of said yokes adapted to clamp the bases of the glasses against the tray, substantially as described.

15 6. In a tray, a base provided with a beaded

edge, a resilient wire the ends of which are secured to the tray, the intermediate portion of the wire being bent to form a series of outwardly-extending stem-receiving yokes, the outer ends of which overlie the said beaded edge, substantially as described.

25

7. A tray, having a series of stem-receiving wire yokes resiliently attached at their inner ends to the tray, their outer, yielding ends being adapted to straddle the stems and clamp the bases of the glasses against the tray, substantially as described.

In testimony whereof I have hereunto set my hand.

DAVID H. ALLEN.
